COMBINATION GRINDER AND DISPENSER FOR COFFEE AND THE LIKE

Sheldon Dale, Chicago, Ill., assignor to Cory Corporation, Chicago, Ill., a corporation of Delaware

Application May 17, 1951, Serial No. 15,219

Term of patent 14 years

(Cl. D55—1)

To all whom it may concern:

Be it known that I, Sheldon Dale, a citizen of the United States, residing at Chicago, Cook County, Illinois, have invented a new, original, and ornamental Design for a Combination Grinder and Dispenser for Coffee and the like, of which the following is a specification, reference being had to the accompanying drawing, forming part thereof, wherein:

Fig. 1 is a perspective view, looking toward the front and one side of a combination grinder and dispenser for coffee and the like, showing my new design;

Fig. 2 is a front elevational view thereof;

Fig. 3 is a view in elevation of the side that is hidden from Fig. 1; and

Fig. 4 is a top plan view thereof.

The rear elevation of the machine (not shown) is substantially plain.

I claim:

The ornamental design for a combination grinder and dispenser for coffee and the like, as shown and described.

SHELDON DALE.
